UNITED STATES PATENT OFFICE.

COLOMAN DE KANDÓ, OF BUDAPEST, AUSTRIA-HUNGARY, ASSIGNOR TO
RAILWAY ELECTRIC POWER COMPANY, A CORPORATION OF MAINE.

AUTOMATICALLY-REGULATED LIQUID RHEOSTAT OPERATED BY MEANS OF COMPRESSED AIR

No. 821,418.

Specification of Letters Patent.

Patented May 22, 1906.

Application filed November 27, 1903. Serial No. 182,700.

To all whom it may concern:

Be it known that I, COLOMAN DE KANDÓ,
engineer, a subject of the Emperor of Aus-
tria-Hungary, residing at Budapest, in the
Empire of Austria-Hungary, have invented
5 certain new and useful Improvements in or
Relating to Automatically-Regulated Liquid
Rheostats Operated by Means of Compressed
Air, of which the following is a full and clear
description.

My present invention relates to automatically-regulated liquid rheostats operated by means of compressed air for starting and regulating the speed of induction-motors; and it consists in certain novel parts and combination of parts particularly pointed out in the claims concluding this specification.

In the accompanying drawings I have diagrammatically illustrated the leading features 20 of my invention, which, with the following description, will enable those skilled in the art to practice the same; but it will be understood that a variety of instrumentalities in detail may be employed to embody the principles 25 thereof without departing from the spirit of my invention and without exceeding the scope of my claims.

In the drawings, Figure 1 is a cross-sectional view of apparatus involving my present invention. Fig. 2 illustrates the connection of the apparatus shown in Fig. 1.

The following is a description of the drawings.

35 A is a liquid rheostat of a form now well known in the art (see my Patents No. 677,454, dated July 2, 1901, and No. 733,971, dated July 21, 1903) comprising a reservoir 24 and a chamber 21, containing the electric terminals 22, electrically connected by fluid 40 discharged from the reservoir 24.

1 is the chamber containing compressed air.

16 is a handle controlling the valve C, which when moved in the direction of the arrow first establishes communication between the compressed-air chamber 1 and the chamber 14 and when moved farther compresses the spring 3.

2 is a valve pressed upon its seat by a spring 25.

50 4 is a membrane supporting an abutment controlled by the spring 3, the compression of which is regulated by a rack 26.

27 is a chamber between the valve 2 and the membrane 4.

28 is a pipe leading from the chamber 27 to 55 the chamber 29. The chamber 29 is provided at its top with a membrane 6 and at its bottom with a membrane 5 of smaller area. These membranes carry a valve-case 9 and a spring-controlled valve 32, terminating in a 60 projection 7.

11 is a pivoted armature within the influence of an electromagnet or solenoid 12, the active wire of which is included in the circuit of the field or armature of an induction-motor. 65

13 is a valve controlling communication between the chamber 17 and the reservoir 24, which valve is controlled by a float 30.

15 is a piston controlled by the pressure of air in the chamber 17 and having attached thereto a device for short-circuiting the secondary of an induction-motor when full speed is attained. 70

The operation of the device may be thus described: When the starting-lever 16 is moved in the direction of the arrow, the valve C establishes communication between compressed-air chamber 1 and chamber 14; but this air cannot at once pass into the chamber 17, because the valve 8 is at this time held down by the projection 7, attached to it. When the lever 16 is moved still farther in the direction of the arrow, the spring 3 is compressed, and the valve 2 is thereby opened, admitting compressed air into the chamber 27 through conduit 28 to the chamber 29. The pressure of the air in the chamber 29 acting upon the membranes 5 and 6, the upper one being of larger area, elevates the casing 9, which is attached to both membranes, (because it produces inflation of or toward the larger membrane 6,) so that the projection 7, being thus elevated, opening valve 8 and allowing the compressed air from chamber 14 to pass into chamber 17, and the 75 80 85 90 95

chamber 14 to pass into chamber 17, and the valve 13 being at this time open into the reservoir 24 of the rheostat. The fluid in this reservoir is thus forced into the chamber 21 and, rising in said chamber, establishes electrical contact between the plates 22. As soon as the liquid reaches the bottom of said plates current begins to flow through the motor 50, Fig. 2, and through the solenoid or magnet 12, the effect of which is to attract the armature 11 and to depress the valve-case 9 and the valve 8, thus throttling the admission of compressed air to the chamber 24. The speed with which the liquid-level in the chamber 14 rises is controlled by the valve 13.

ber 21 rises is thus automatically controlled by balancing the current flowing against the pressure of the air within the chamber 29. When the liquid-level in the chamber 21 rises 5 to a certain point, or, in other words, when the liquid-level in chamber 24 falls to a given point, the float 30 permits valve 13 to close and prevents the admission of any further quantity of compressed air to the chamber 24, 10 and hence prevents any further decrease of resistance in the motor-circuit. Up to this time the pressure in the chamber 17 is relatively slight, corresponding approximately only to the differences of levels of the liquid 15 in the rheostat-chambers. It now, however, rapidly rises to maximum pressure, and in so doing actuates the short-circuiting device 34 and 15, connected in the circuit of the secondary of the motor, and normal or full- 20 speed running conditions are established. Should any loss of pressure occur through leakage from the chamber 24, it will automatically be compensated by the further admission of compressed air through the valve 13, 25 as will be readily understood. Automatic regulation also takes place when the current-flow increases so rapidly that the armature 11 is depressed too quickly, since in this case the valve 32 is opened, thus discharging the 30 compressed air into the outer atmosphere, whereupon the normal or automatic regulation through the valve 8 continues to take its course, as described. The pressure of the air in chamber 27, and hence the pressure in 35 chamber 29, which is in free communication therewith, is determined by the degree to which the spring 3 is compressed, or, in other words, by the position of the handle 16, since the abutment 33 is controlled as to position 40 by the degree of compression of the spring 3, acting against the pressure of compressed air within the chamber 27 upon the diaphragm 4. Assuming a given degree of compression of the spring 3, the position of the valve 2 will 45 be determined by the pressure in the chamber 27, since when a certain pressure is reached—say the pressure exerted by the spring 3—said valve will close. Since the degree of pressure in the chamber 29 acting, 50 as it does, against the force of the armature 11 determines the position of the valve 8, and therefore the admission of compressed air to the rheostat, it is plain that the speed with which the liquid rises in the rheostat (which 55 corresponds with the speed with which the resistance diminishes in the motor) is determined by the position of the controller-handle 16, and it is also plain that with the handle in a given position the starting-current is 60 maintained constant, while the resistance in the armature-circuit varies.

In stopping the motor the handle 16 is moved in the reverse direction, as will be readily understood. When the spring 3 is released, the pressure in chamber 27 forces the 65

abutment 33 outwardly away from the inner end of double valve 2, and thus opening communication with the outside air.

Having thus described my invention, what I claim as new, and desire to secure by Letters Patent, is—

1. A liquid rheostat combined with a supply of compressed air, a throttle-valve between said compressed-air supply and said rheostat adapted to control the supply of compressed air to the rheostat; said valve being controlled by the combined action of the electric current flowing through said rheostat and compressed-air pressure. 75

2. A liquid rheostat combined with a supply of compressed air, a throttle-valve between said compressed-air supply and said rheostat adapted to vary the rate of supply of compressed air to the rheostat; said valve being controlled by the combined action of the electric current flowing through said rheostat and compressed air. 80

3. A liquid rheostat combined with a supply of compressed air, a hand-operated valve for controlling the connection between said supply and said rheostat, a throttle-valve located in said connection, an electric device in circuit with said rheostat, a device operated by air-pressure and operating in opposition to said electric device to control the action of said throttle-valve. 90

4. A liquid rheostat combined with a supply of compressed air, a hand-operated valve for controlling the connection between said supply and said rheostat, a throttle-valve located in said connection and a supplemental device operated by compressed air to control the action of the throttle-valve. 100

5. A liquid rheostat combined with a supply of compressed air, a hand-operated valve for controlling the connection between said supply and said rheostat, a throttle-valve located in said connection, a device normally holding said throttle-valve closed and means for actuating said device to permit said throttle-valve to open. 105

6. A liquid rheostat combined with a supply of compressed air, a throttle-valve located in the connection between said rheostat and said compressed-air supply, a supplemental device operated by compressed air for controlling the position of said throttle-valve, a hand-operated valve for controlling the connection between said supply and said rheostat and also for controlling the flow of compressed air to said supplemental device. 115

7. A liquid rheostat combined with a supply of compressed air, a throttle-valve located in the connection between said rheostat and said compressed-air supply, a supplemental device operated by compressed air for controlling the position of said throttle-valve and a hand-operated device which initially controls the connection between said supply and said rheostat and subsequently 120

controls the connection between said supply and said supplemental device.

8. In combination with a liquid rheostat, a supply of compressed air, an electric device in circuit with said rheostat and a throttle-valve in the connection between the compressed-air supply and the rheostat, of a device controlling said throttle-valve comprising a chamber having flexible walls of unequal area.

9. In combination with a liquid rheostat, a supply of compressed air, an electric device in circuit with said rheostat and a throttle-valve in the connection between the compressed-air supply and the rheostat, of a device controlling said throttle-valve comprising a chamber having flexible walls of unequal area; the wall of smaller area being subjected to equal pressures on opposite sides thereof.

10. In combination with a liquid rheostat, a supply of compressed air, an electric device in circuit with said rheostat and a throttle-valve in the connection between the compressed-air supply and the rheostat, of a device controlling said throttle-valve and a relief-passage controlled by a check-valve.

11. In combination with a liquid rheostat, a supply of compressed air, an electric device in circuit with said rheostat and a throttle-valve in the connection between the compressed-air supply and said rheostat, of a device controlling said throttle-valve, a check-valve controlling a passage communicating with the compressed-air chamber of the rheostat and the open air.

12. A liquid rheostat combined with a supply of compressed air, a throttle-valve between said compressed-air supply and said rheostat, adapted to control the supply of compressed air to said rheostat, said valve being controlled by the combined action of a force automatically exerted by the current flowing opposed by a variable force under the control of the operator.

13. A liquid rheostat combined with a sup-

ply of compressed air, a throttle-valve between said compressed-air supply and said rheostat, adapted to control the supply of compressed air to the rheostat, said valve being controlled by the combined action of the electric current flowing through said rheostat, and compressed-air pressure with mechanism controlled by the operator for varying said compressed-air pressure.

55

14. In combination with a liquid rheostat, a supply of compressed air, a device in circuit with said rheostat operated by the current flowing, a throttle-valve in the connection between the compressed-air supply and the rheostat, of a chamber having flexible walls of an equal area whereby the pressure of air within the same opposes the force exerted by the current to close the throttle-valve, and mechanism under the control of the operator whereby the pressure within said chamber may be varied.

60

15. The combination with an electric motor of a starting resistance, means for varying said resistance, said means being controlled by an electrically-operated device in the circuit of the motor, a mechanically-operated device acting in opposition thereto, and means for adjusting said mechanically-operated device whereby the rate of variation of the starting resistance is controlled.

70

16. A starting-rheostat for induction-motors comprising a variable resistance interposed in the secondary of the motor, means for automatically diminishing said resistance as the speed of the motor increases, a device actuated by the current flowing to maintain the starting-current of substantially constant value while the resistance is changing and means for variably controlling said constant-current value.

75

In witness whereof I have hereunto set my hand in the presence of two witnesses.
